RAILWAY SWITCH OPERATING APPARATUS

Herbert L. Bone, Forest Hills, Pa., assignor to
The Union Switch & Signal Company, Swiss-
vale, Pa., a corporation of Pennsylvania

Application November 27, 1937, Serial No. 176,837

23 Claims. (Cl. 246—291)

My invention relates to railway switch operating apparatus, and particularly to apparatus for operating spring switches.

One object of my invention is to provide means which, when a train trails a spring switch, becomes effective to force the movable rails of the switch to, and hold them in, positions opposite to their initially set positions until after the train has completely passed the switch, whereupon the movable rails are permitted to return to their initially set positions.

Another object of my invention is to provide means of the type described which will not interfere in any way with manual operation of the switch.

A further object of my invention is to provide means of the type described which is adapted to function in connection with a mechanical facing point lock of the type in which the flexure 20 of the switch rails is used to actuate the lock to its unlocking position when a train trails the switch, and which employs for its actuation a part of the lock releasing linkage.

Other objects and characteristic features of my invention will appear as the description proceeds.

I shall describe one form of apparatus embodying my invention, and shall then point out the novel features thereof in claims.

30 In the accompanying drawings, Fig. 1 is a top plan view showing a railway switch provided with one form of switch operating mechanism embodying my invention. Fig. 2 is an enlarged plan view, partly in section, of the operating mechanism shown in Fig. 1. Fig. 3 is a sectional view taken substantially on the line III—III of Fig. 2. Fig. 4 is a detail sectional view illustrating the biasing device 36 forming a part of the apparatus shown in Fig. 2. Fig. 5 is a sectional view 40 of the buffering device D and pump P forming part of the apparatus shown in Figs. 2 and 3. Fig. 6 is an enlarged top plan view of a portion of the apparatus shown in Fig. 2.

Similar reference characters refer to similar parts in each of the several views.

Referring first to Fig. 1, the reference character A designates a railway switch comprising, as usual, two fixed rails 1 and 1^a and two movable rails 2 and 2^a. The fixed rails 1 and 1^a are laid 50 on tie plates 3 and are secured to crossties 4 in the usual manner. The movable rails 2 and 2^a are fastened together by a front rod 5, a head rod 6, a bridle rod 7, and a tie rod 8, and may be moved into a normal or a reverse position by 55 means of an operating rod 9 which is connected

with the head rod 6 through the medium of the usual switch basket 10. When the switch occupies its normal position in which it is shown in Fig. 1, the movable rail 2 engages the fixed rail 1, and the movable rail 2^a is spaced a slight distance from the fixed rail 1^a. When the switch is reversed, however, the movable rail 2^a then engages the fixed rail 1^a, and the movable rail 2 is spaced from the fixed rail 1.

Associated with the switch A is a switch operating mechanism B comprising a main casing 11 which is bolted or spiked to the ties 4 adjacent the outer side of the rail 1, and an auxiliary casing 12 which is secured to the left-hand end of the casing 11. The main casing 11 is provided 10 with a removable cover 13 while the auxiliary casing 12 is provided with a removable cover 14.

Extending downwardly through the main casing 11 is a rotatable spindle or switch actuating shaft 16, and attached to the lower end of this 20 shaft is an adjustable crank 17 which is pivotally connected with the previously described operating rod 9, the parts being so proportioned that rotation of the shaft 16 through an angle of approximately 90° will move the switch between its 25 normal and reverse positions.

The lower portion of the shaft 16, that is the portion within the casing 11, is made round, and is journaled in a bearing 18 provided in the bottom of the casing 11, and in a star block 19, 30 which in turn, is journaled in a bearing 20 formed in the top of the casing 11. The portion of the shaft 16 above the top of the star block bearing, however, is made square and has a somewhat smaller cross sectional area than the lower portion of the shaft.

Secured to the square portion of the shaft 16 is a square sleeve 21, and slidably mounted on this sleeve is an outer sleeve 22 which is provided with a square opening to receive the inner sleeve 40 so that both sleeves and the shaft are constrained to rotate together.

When the outer sleeve 22 occupies its lowermost position on the inner sleeve, in which position it is shown in the drawing, a squared portion 45 23 formed on the lower end of the outer sleeve enters a squared recess or socket 24 formed in the upper end of the star block 19, and under these conditions, the outer sleeve, and hence the shaft 16, is connected with the star block so 50 that any rotation of the shaft will cause corresponding rotation of the star block. When, however, the outer sleeve 22 is moved to an upper position on the inner sleeve, the squared portion 23 on the lower end of the outer sleeve becomes 55

disengaged from the socket 24 in the star block, and the two sleeves and the shaft are then free to rotate as a unit independently of the star block.

5 The outer sleeve 22 is arranged to be moved between its two extreme positions by means of a hand lever 27 which also serves as a means for rotating the switch actuating shaft 16 between its two extreme positions. This lever is bifurcated at one end, and the bifurcations therefore are disposed on opposite sides of a square portion formed at the upper end of the outer sleeve, and are pivoted at their free ends on a pin 28 mounted in a lug 29 formed on the inner sleeve 10 15 21. Each bifurcation extends between a pair of lugs 30 which are secured to the associated side of the outer sleeve 22, only one pair of lugs being visible in the drawing. The parts are so proportioned that, when the lever 27 is rotated about 20 the pin 28 to a depending position in which it is shown in the drawing, the outer sleeve 22 will be moved to its lowermost position on the inner sleeve, but that, when the lever is rotated about the pin 22 to a substantially horizontal position, 25 the outer sleeve will then be moved to its upper position on the inner sleeve. It follows that the switch actuating shaft 16 will be connected with or disconnected from the star block 19 according as the lever 27 occupies its depending or its 30 horizontal position, and that, when the lever occupies its horizontal position, the shaft 16 may be rotated between its two extreme positions to move the switch points to their corresponding extreme positions by rotating the lever about the 35 axis of the shaft, without causing rotation of the star block.

When the hand lever 27 occupies its depending position which position is its normal position, it may be locked in this position by placing a padlock 31 or other suitable locking device through a 40 hole 32^a formed in the outer end of a lug 32 which is fastened to the outer sleeve 22 and which passes through a suitable slot 33 in the lever 27. A suitable signal, here shown as a pair of vanes 45 34, positioned 90° with respect to each other in plan view, is fastened to the upper end of the switch actuating shaft 16, and serves to accurately indicate at all times the position of the switch.

50 The star block 19 is constantly biased to the position in which it is shown in the drawings by means of two biasing devices or spring units 35 and 36 which are disposed in the right-hand end of the casing 11. These biasing devices are 55 similar, and a description of one will therefore suffice for both. Referring particularly to the biasing device 36 shown in Fig. 4, this biasing device comprises a cylindrical housing 37 which is provided at one end with a pair of spaced lugs 60 38 and at the other end with an end plate 39. Located within the housing 37 are two coil springs 40 and 41. Interposed between the left-hand end of the springs 40 and 41 and the end plate 39 is a member 42 having a centrally located hole 43. 65 A similar member 44 provided with a centrally located hole 45 is interposed between the other end of the springs 40 and 41 and the right-hand end of the housing 37. A rod 46 passes through the holes 43 and 45 in members 42 and 44 and 70 also passes through a hole 47 in end plate 39. The upset end 48 of rod 46 engages the outer surface of the member 44. Threaded on rod 46 is a sleeve 49 which enters the hole 47 in the end plate 39 and bears against the outer surface 75 of member 42. The end plate 39 is screwed into

or out of the casing 37 until the springs 40 and 41 are under the desired pressure, and the end plate is then locked in its adjusted position by a bolt 50. Sleeve 51 is then screwed onto rod 46 until it engages the member 42 when the upset 5 end 48 of the rod is tight against the member 44. Sleeve 51 is then locked in its adjusted position by means of the nut 52. With the biasing device constructed in this manner, it will be apparent that the two springs 40 and 41 both act 10 to bias the rod 46 to the position shown, and that movement of the rod in either direction will act to compress these springs beyond their initial compression.

The right-hand end of the biasing device 36 is 15 pivotally attached to the casing 11 by means of a pin 53 which passes through aligned apertures in the lug 38, and the right-hand end of the biasing device 35 is similarly attached to the casing 11 by means of a pin 54. The free end of 20 the rod 46 of each of the biasing devices 35 and 36 is operatively connected with the star block 19 by means of a pin 55 which passes through an eye 56 adjustably screwed onto the rod, and through aligned apertures in vertically spaced lugs 57 provided on the star block. The eyes 56 are so adjusted that both biasing devices will act to bias the star block 19 to the position in which it is shown in the drawings, and the parts are so proportioned that, when the star block occupies the position shown and the switch is connected with the star block, the switch will be yieldably urged to which ever extreme position it then occupies. The parts are further so proportioned that, if the star block is rotated away 35 from the position shown in a clockwise direction as viewed in Fig. 2, through an angle corresponding to the switch stroke, the force exerted on the star block by the biasing device 35 will continue to increase as the star block approaches its 40 clockwise extreme position, but the biasing device 36 will function as a toggle, and will act to oppose the movement of the star block until the star block has been rotated halfway to its clockwise extreme position, whereupon the biasing device 45 36 will then act to assist the further movement of the star block. The parts are still further so proportioned that, if the star block is rotated away from the position shown in a counterclockwise direction, as viewed in Fig. 2, through an 50 angle corresponding to the switch stroke, the force exerted on the star block by the biasing device 36 will continue to increase as the star block approaches its counterclockwise extreme position, but the biasing device 35 will function 55 as a toggle and will act to oppose the movement of the star block until the star block has been rotated halfway to its counterclockwise extreme position, whereupon this latter biasing device will then act to assist the movement of the star block. 60 It will be obvious that the force exerted by the biasing device 35 tending to restore the star block to the normal position shown when the star block has been rotated to its counterclockwise extreme position, as viewed in Fig. 2, will exceed 65 the opposing force exerted by the biasing device 36, and that the force exerted by the biasing device 36 tending to restore the star block to the position shown when the star block has been rotated to its counterclockwise extreme position, 70 as viewed in Fig. 2, will exceed the opposing force exerted by the biasing device 35, and it follows, therefore, that, when the star block has been rotated away from the position shown in either direction, as soon as the force which caused 75

the rotation of the star block is removed, the biasing devices will act to restore the star block to the position shown.

Reciprocably mounted in the bottom of the casing 11 is a locking device 60 which as here shown comprises two spaced cross members 60^a and 60^b connected together by means of a pair of spaced stud bolts 60^c and 60^d. A third cross member 60^e is adjustably secured to the threaded 10 left-hand ends of the stud bolts 60^c and 60^d by means of nuts 60^f and this latter member is provided on its left-hand side with an integral rectangular locking plunger 60^g. The member 60^a is provided with a centrally located hole 60^h. 15 The locking plunger 60^g extends into the casing 12 and is adapted to cooperate with a lock rod L which is slidably mounted in the casing 12 at right angles to the locking plunger. The lock rod L is of standard construction and comprises two 20 longitudinally adjustable bars 63 and 64 attached at one end to the front rod 5 of the switch A, and provided with two registering notches 65 so disposed that these notches will align with the locking plunger 60^g when and only when the 25 switch occupies its normal extreme position in which it is shown in the drawings.

The locking device 60 is arranged to be moved in a manner which will be described hereinafter, between a left-hand extreme position in which the locking plunger 60^g is within the notches 65 in the lock rod L, and a right-hand extreme position in which the locking plunger 60^g is withdrawn from the notches 65, and it will be apparent that, when the locking device is moved to 35 the position in which the locking plunger is withdrawn in the notches, the switch will be positively locked in its normal extreme position, but that, when the locking device is moved to the position in which the locking plunger is withdrawn from the 40 notches in the lock rod, the switch will then be unlocked.

The bolt members 60^c and 60^d of the locking device 60 are slidably mounted intermediate their ends in suitable lugs 66 and 67, respectively, which 45 project upwardly from the bottom of the main casing 11, and surrounding each bolt between the cross member 60^b and the associated lug 66 or 67 is a partly compressed coil spring 68 which 50 constantly biases the locking device 60 to its left-hand extreme position.

A crank 69^a is secured to a shaft 70 mounted in a pair of spaced lugs 71 projecting from the side of the casing 11, and this crank extends downwardly and is provided at its lower end with a 55 rounded portion 69^b which cooperates with a lateral extension 60^j provided on the cross member 60^e, in a manner which will be described hereinafter. A second crank 69^c is also secured to the shaft 70, and this latter crank extends toward 60 the right and is pivotally connected at its free end by means of a pin 72 with the lower end of a vertical connecting rod 74.

The connecting rod 74 is shaped as shown, and 65 comprises an integral offset portion 74^a which is rectangular in cross section. This offset portion extends upwardly with a sliding fit through a rectangular guideway 75 formed in the top wall of the casing 11, and is provided at its upper end with a lateral extension 74^b which overlies 70 and co-operates with, an annular flange 77 formed on the sliding sleeve 22 directly above the squared portion 23. A two-piece collar 78 is bolted to the sliding sleeve 22 some distance above the annular flange 77 and lateral extension 74^b, 75 and extending downwardly from this collar is an

integral frusto-conical hood 79 which completely encloses the upper part of the offset portion 74^a of the connecting rod 74 and the annular flange 77, thus protecting these parts from dirt, moisture, etc.

The lower end 74^c of the offset portion 74^a of the connecting rod 74 overlies and cooperates with a cam member 80 formed integrally with the star block 19. This cam member has a semi-circular periphery and its upper surface curves 10 downwardly from each end toward the center, as shown in Fig. 2. Only one-half of this cam member is visible in Fig. 2 because the other half is directly back of the half shown, but the half which is not visible is similar to the half which 15 is visible.

The parts are so proportioned that, when the sliding sleeve 22 occupies its lowermost position, and the star block 19 occupies the position to which it is biased by the biasing devices 25 and 26, as shown in the drawings, the connecting rod 74 will move by gravity to the position in which it is shown in the drawings, which position I shall hereinafter refer to as its "lowermost" position. The parts are further so proportioned that, when 25 the connecting rod 74 occupies its lowermost position, the underside of the lateral extension 74^b of the connecting rod will engage the upper side of the annular flange 77, the lower end 74^c of the offset portion 74^a will engage the upper face 30 of the cam member 80 at the lowest point of the cam face, and the crank 69^a will be rotated to a position in which the rounded portion 69^b would engage the offset portion 60^j of the cross member 60^e of the locking device 60 if the 35 locking device were then moved to its extreme left-hand position by the biasing spring 68.

The locking device 60, in addition to being operatively connected with the sliding sleeve 22 and the star block 19 in the manner just described, is also operatively connected with the tie rod 8 by means of linkage which I shall now describe.

As here shown, this linkage includes a plunger bolt 81 (see Figs. 1 and 2) which extends with 45 some clearance through the hole 60^h in the cross member 60^a of the locking device 60, and the head of which bolt cooperates with the left-hand side of the cross member 60^a. The threaded right-hand end of the plunger bolt 81 is adjust- 50 ably connected by means of a turnbuckle 82 with one end of a link 83, the other end of which link is pivotally connected with the long arm 84^a of a bell crank lever 84. The bell crank lever 84 is pivotally supported in a crank stand 85, and 55 has its short arm 84^b pivotally connected with one end of an operating rod 86. The other end of the operating rod 86 is connected with the previously described tie rod 8 by means of a stand- 60 ard switch basket 87.

The tie rod 8 may be located at any suitable location, but will be preferably located approximately half-way between the heel and the point of the switch. The base 88 of the crank stand 85 is secured both to a gauge plate 89 and to the 65 bed plate 15 upon which the mechanism B is mounted, and it will be apparent, therefore, that any loss of adjustment between the parts due to creepage of the ties is prevented. The linkage is so adjusted that, when the switch occupies its 70 normal extreme position, the head of the plunger bolt 81 will engage the end member 60^a when the locking plunger has been moved to the desired locking position within the notches 65 in the lock rod L.

If desired, a suitable circuit controller may be provided in the casing 12 to indicate when the locking plunger occupies its proper locking position. This circuit controller forms no part of my present invention, and is not, therefore, shown in the drawings. This circuit controller may, however, be similar to that shown and described in Letters Patent of the United States No. 1,989,-128, granted to me on January 29, 1935.

10 The apparatus also includes a fluid pressure device D and a pump P, the function of which device and which pump will be made clear presently. The device D and pump P are shown in detail in Fig. 5, and as there illustrated, the 15 device D comprises a cylinder 91 formed in a suitable casing 90. The cylinder 91 is closed at its left-hand end by a cylinder head 92, and extending into the cylinder through a stuffing box 93 and an opening 94 provided in the cylinder 20 head is a piston rod 95, the inner end of which is attached by means of a nut 96 to a reciprocable piston 97. The right-hand side of the piston 97 is provided with an annular flange 98 which forms a cylindrical recess 99, and secured 25 to the flange 98 is a flexible diaphragm 100. The diaphragm 100 is biased to an outward position by a compressed coil spring 101, and constitutes with the spring a pressure accumulator for maintaining a constant pressure on the piston 97 under certain conditions which will be pointed out 30 hereinafter.

Located in the casing 90 above the cylinder 91 is a reservoir 104 which is constantly connected with the cylinder 91 at the left-hand end 35 of the cylinder by a port 105. The reservoir is also connected with the cylinder 91 on the right-hand side of the piston by means of a check valve 106, passageways 107 and 127, and a check valve 108, the check valves being so arranged 40 that fluid can flow from the reservoir to the cylinder, but that the flow of fluid from the cylinder to the reservoir is prevented. The reservoir is further connected with the cylinder 91 on the right-hand side of the piston through a 45 port 109, a regulating valve 110, and a strainer 111. The reservoir and cylinder are both intended to be filled with a suitable fluid such as oil, and in order to permit the insertion of fluid into the reservoir and cylinder, the reservoir 50 wall is provided with a hole 112 which is normally closed by a screw plug 113.

The regulating valve 110 may have any desired construction, and may, for example, be similar to the valve 47 shown in Letters Patent of the 55 United States No. 1,830,803, granted to W. C. McWhirter, on November 10, 1931, for Railway switch operating apparatus. Since this valve is similar to that shown in the said McWhirter patent, it is believed to be sufficient for purposes of 60 the present disclosure to state that this valve comprises a hollow valve body provided with a plurality of restricted orifices of different sizes which extend through its side in radial spaced relation and any one of which may be brought 65 into registration with the port 109 by rotating the valve body about its axis to different positions.

With the fluid pressure device constructed in the manner just described, it will be apparent 70 that, if the piston 97 is moved toward the left, the fluid on the left-hand side of the piston will flow freely into reservoir 104 through the port 105, and from the reservoir 104 through the check valve 106, passageways 107 and 127, and 75 check valve 108 into the cylinder 91 on the right-

hand side of the piston, but that, if the piston is moved in the opposite direction, the check valve 108 will seat and the fluid on the right-hand side of piston 97 will then be constrained to flow through the strainer 111, regulating valve 110, and port 109 into the reservoir 104, thus limiting the rate of movement of the piston to the rate at which fluid can flow through the regulating valve. This rate can, of course, be varied by changing the setting of the regulating valve. 10

The pump P comprises a vertically disposed cylinder 115 formed in a cylindrical casing 116 secured to the casing 90 by means of a web 117 formed integrally with the two casings. The upper end of the cylinder 115 is closed by a screw 15 plug 118, and extending into the lower end of the cylinder through a packing gland 119 is an elongated cup-shaped plunger 120. The plunger 120 is adapted to be at times reciprocated, and to this end the plunger is constantly biased into 20 engagement with an operating lever 121 (see Fig. 3) by means of a compressed coil spring 122 interposed between the screw plug and the lower end of the plunger. The cylinder on the upper side of the plunger is constantly connected with 25 the port 107 by a passageway 123, and it will be seen, therefore, that downward movement of the plunger will suck oil from the reservoir 104 into the cylinder 115 through the check valve 106 and the passageways 107 and 123, whereas upward 30 movement of the piston 120 will force the fluid that was previously sucked into the cylinder 115 through the passageways 123 and 127 and the port 108 into the cylinder 91 on the right-hand 35 side of the piston 97. It follows, therefore, that reciprocating action of the plunger will pump 40 oil out of the reservoir 104 and into the cylinder 91 of the fluid pressure device D on the right-hand side of the piston 97. A recess 135 is formed around the lower end of the plunger 120 above the packing gland 119, and this recess is 45 connected by means of a passageway 124 with the port 109, whereby any fluid that leaks past the plunger will be returned to the reservoir. 50

The pump P is pivotally mounted in a suitable bearing 125 secured to the one end wall of the 45 casing 11, and serves to pivotally attach the device D to the casing, whereas the piston rod 95 is pivotally attached to the star block 19 by means of an eye 126 and the pin 55. It will be 55 seen, therefore, that the fluid pressure device will permit free rotation of the star block in either direction away from the position shown, but that rotation of the star block by the biasing devices 35 and 36 will be retarded by the fluid pressure device. 60

The lever 121 with which the plunger 120 cooperates is bifurcated at the end opposite to the plunger, as best seen in Fig. 6, and is pivotally attached to the casing 11 by means of a pin 130 60 mounted in a pair of spaced upstanding lugs 131 provided on the bottom wall of the casing. A roller 132 is secured to the lever between the bifurcations adjacent their joined ends by means of a pin 133, and this roller cooperates with a 65 cam 134 secured to the cross member 60^a of the previously described locking device 60. The left-hand end of the cam 134 is formed with an inclined cam face 134^a, and the parts are so proportioned that, when the locking plunger 60 occupies its locking position in which it is shown in the drawings, the roller will engage the cam at its flat upper surface, but that, when the locking device 60 occupies its unlocking position, the cam will then be out of engagement with the roller. 70 75

The parts are further so proportioned that, when the roller is engaging the cam at its flat upper surface, the lever L will be rotated in a counterclockwise direction, as viewed in Fig. 3, to an upper extreme position in which the pump plunger is forced to its upper extreme position, but that, when the roller is out of engagement with the cam, the lever will then be permitted to rotate, due to its weight and to the bias of the pump spring 122 acting through the pump plunger 120, to a lowermost position in which the pump plunger occupies its lower extreme position.

The operation of the apparatus as a whole is as follows: As shown in the drawing, the movable rails of the switch are in their normal extreme positions, and the hand lever 27 is locked in its depending position by means of padlock 31. Under these conditions, the outer sleeve 22 is held in its lowermost position on the inner sleeve 21, and the star block 19 is accordingly connected with the switch actuating shaft 16 so that the biasing devices 35 and 36 are effective to hold the movable rails of the switch in their normal positions. Furthermore, under these conditions, the connecting rod 74 is held by gravity in its lowermost position, and the locking device 60 is held in its locking position by the biasing springs 68. As was previously pointed out, when the locking device 60 occupies its locking position, the movable rails of the switch are locked in their normal positions, and the plunger of the pump P occupies its lowermost extreme position.

I shall now assume that it is desired to reverse the switch A. To do this, the padlock 31 is first removed from the hole 32^a in the lug 32 to unlock the hand lever 27, and the hand lever 27 is then raised to its horizontal position. This preliminary movement of the hand lever raises the sliding sleeve 22 from its lowermost position in which it is shown in the drawings to its uppermost position, and as was previously described, when the sliding sleeve is moved to its uppermost position, the squared portion 23 on the lower end of this sleeve becomes disengaged from the socket 24 in the upper end of the star block 19, thus disconnecting the star block, and hence the biasing devices 35 and 36 and the fluid pressure device D from the switch actuating shaft, so that the switch actuating shaft is then free to rotate without any opposition from the biasing and buffering devices. Furthermore, when the sliding sleeve 22 is moved to its upper position, the annular flange 7 on the lower end of this sleeve operates with the lateral extension 74^b on the connecting rod 74, to move the connecting rod 74 to its uppermost position, and this movement of the connecting rod, in turn, acts through the cranks 69^c and 69^d, to move the locking device 60 from its normal locking position in which it is shown in the drawings to a position in which the locking plunger 60^e is completely withdrawn from the notches 65 in the lock rod L, thus unlocking the switch, and at the same time permitting the pump operating lever 121 to rotate to its lowermost position. The movement of the pump operating lever under these conditions, however, has no effect on the remainder of the switch operating apparatus, other than to permit the pump plunger to descend under the bias of the spring 120 to its lowermost extreme position. The biasing and buffering devices now being disconnected from the switch actuating shaft and the switch being unlocked, the hand lever is next rotated

through an angle of approximately 90° in a counterclockwise direction. This intermediate movement of the hand lever rotates the switch actuating shaft 16 to the extreme position opposite to that in which it is shown in the drawing, thereby reversing the movable rails of the switch in the manner previously described. As the movable rails move to their reverse positions, the linkage which connects the locking device 60 with the tie rod 8 is actuated in such manner that the plunger bolt 81 is moved toward the right, and as soon as the plunger bolt has moved as far as the locking device was previously moved by the crank 69^a, the plunger bolt engages the end member 60^a of the locking device 60, and during the balance of the movement of the plunger bolt, the locking device will be moved with the plunger bolt, so that, when the switch reaches its full reverse position, the locking device will be moved to its extreme right-hand position. The switch points now being fully reversed, the hand lever 27 is next restored to its depending position. This final movement of the hand lever, of course, restores the sliding sleeve 22 to its lowermost position, thus reconnecting the star block 19 with the switch actuating shaft 16, and at the same time permitting the connecting rod 74 to return by gravity to its lowermost position. After the hand lever has been restored to its depending position, it may, if desired, be relocked in this position by again inserting the padlock 31 in the hole 32^a in the lug 32.

If, when the switch has been moved to its reverse position in the manner just described, it is desired to restore the switch to its normal position, the hand lever 27 is first raised to its horizontal position, and is then rotated in a clockwise direction through an angle of 90° as viewed in Fig. 1, and is finally restored to its depending position and relocked in this position. The operation of the various parts of the apparatus under these conditions is just the reverse of that described above and will be readily understood from the foregoing description and from an inspection of the drawings without further description.

I shall now assume that the parts are in their normal positions, as shown in the drawings, and that a train trails the switch. As the leading wheels of the train roll along the fixed rail 1, and the movable rail 2^a, the movable rails 2 and 2^a are forced over laterally, but before a sufficient force is developed at the points of these rails to overcome the opposing force of the biasing devices 35 and 36 and cause the point of the movable rail 2 to move out of engagement with the fixed rail 1, the movable rails, being somewhat resilient, become bent, so that with the usual standard split switch, the tie rod 8 will be moved upwardly, as viewed in Fig. 1, three-quarters of an inch or more. This movement of the tie rod 8 acting through the switch basket 87, operating rod 86, bell crank lever 84, link 83, and plunger bolt 81 moves the locking device 60 in opposition to the bias of the springs 68, a sufficient amount to completely withdraw the locking plunger 60^e from engagement with the notches 65 in the lock rod L, thus unlocking the switch. As a result, when the leading wheels of the train have reached the position in which a sufficient force is developed at the points of the movable rails to cause the point of the movable rail 2 to move out of engagement with the fixed rail 1, the movable rails will be unlocked, and the rails will therefore be forced away from

their normal positions by the wheels of the train in exactly the same manner as they would be if no point lock were provided. The movement of the movable rails away from their normal positions acts through the operating rod 9 and crank 17 to rotate the shaft 16 in a counterclockwise direction, and this rotation of the shaft 16, in turn, rotates the associated sleeves 21 and 22 and the star block 19 in the same direction. The rotation of the star block 19 actuates the biasing devices 35 and 36 in the manner previously described, so that the biasing device 36 now tends to constantly return the movable rails to their normal position, and the biasing device 35 exerts a force on the movable rails which opposes that due to the biasing device 36 thereby decreasing the total force tending to return the movable rails to their normal positions. The rotation of the star block 19 also actuates the fluid pressure device D which, as was previously pointed out, permits free and unrestricted rotation of the star block in a direction to compress the springs of the biasing devices but acts to retard movement of the star block by the biasing devices. The springs 68 of the locking device 60 are so proportioned that, as the wheels of the train continue to trail the switch, they will act, through the linkage which connects the biasing device with the tie rod 8, and the tie rod 8, to exert a sufficient force on the movable rail 2^a to bow or spring this movable rail to less than wheel gauge width between the passage of successive car trucks, and it will be seen, therefore, that, as successive car trucks pass the tie rod 8, they will cause the locking device 60 to oscillate back and forth. The parts are so proportioned that this back and forth oscillation of the locking device will cause the lever 121 to oscillate between its two extreme positions, and will thus actuate the pump P, it being noted that the upward stroke of the pump plunger is caused by the force exerted by the biasing springs 68, and not by the displacement of the point rail to wheel gauge position. The oscillating movement of the pump will pump fluid out of the reservoir 104, and into cylinder 91 of the fluid pressure device D on the right-hand side of the piston 97, and will thus build up in the cylinder 91 on the right-hand side of the piston a force which forces the switch points to their fully trailed positions and holds them there until after the train has completely passed the switch. It should be noted that the pressure accumulator 100 in the piston 98 acts to maintain a constant pressure in the cylinder 91 between the successive strokes of the pump. It should also be noted that, since the upward stroke of the pump plunger is due to the bias of the springs 68, rather than to the movement of the point rail to wheel gauge position as the wheels move past the tie rod 8, after the points have been completely reversed and the pump plunger is unable to move upwardly any further, no additional load is placed upon the flanges of the wheels, but instead the movable rail 2^a is held in its full gauge position. It will be seen, therefore, that the fluid pressure device D will not oppose the movement of the movable rails away from their normal positions, but on the contrary will act to force the movable rails to their reverse positions and hold them there during the entire time the train is trailing the switch. The rotation of the star block 19 caused by the displacement of the movable rails from their normal positions further causes the cam 80 to rotate and, due to the previously described

shape of this cam, it will be apparent that this rotation of the cam will force the connecting rod 74 upwardly from its normal position. The parts are so proportioned that this upward movement of the connecting rod will rotate the crank 69^a in a counterclockwise direction to a position in which, if the locking device were not already moved to an unlocking position by the linkage which connects the locking device with the tie rod 8, the bell crank lever would move the locking device to a position in which the locking plunger 60^a of the locking device would be just clear of the notches 65 in the lock rod L. However, since the locking device has already been moved to an unlocking position, there is no contact between the bell crank lever and the locking device under these conditions. After the train has completely passed the switch, the displacing force of the wheels will, of course, be removed and the leakage of oil through the regulating valve 110 will then permit the plunger 120 to slowly move to its upper position and the piston 97 of the buffering device to move to its right-hand position, thus permitting the biasing devices to slowly return the movable rails to the positions which they occupied before the train started to trail the switch. During the return movement of the movable rails, the star block 19 will, of course, slowly return to the position in which it is shown in the drawing, thus permitting the connecting rod 74 to return by gravity to its lowermost position. Furthermore, during the return movement of the movable rails, the linkage which connects the locking device 60 with the tie rod 8 will permit the biasing spring 68 to slowly return the locking device toward its locking position, and since there is no deflection of the movable rails under these conditions, the locking plunger 60^a will be moved into engagement with the side of the lock rod L before the movable rails have reached their full normal position in which the lock rod is in the proper position for the notches 65 therein to receive the locking plunger. As a result, after the locking plunger has once moved into engagement with the side of the lock rod, the locking plunger will slide along the side of the lock rod until the notches 65 in the lock rod move into alignment with the locking plunger, at which time the energy stored in the compressed springs 68 will force the locking plunger to its normal locking position, thus restoring the switch to its normal locked condition.

The switch is not intended to be locked when it is moved to its reverse position by the switch operating mechanism B, but it should be particularly pointed out, that the apparatus of the switch operating mechanism is symmetrical about the center line which is parallel to the track rails and, as a result, the movement can be arranged to permit the switch to be locked in the reverse position from that shown in the drawings and trailed when it occupies this position merely by changing the positions of the rods which connect the operating mechanism with the switch. The operation of the apparatus when the rods which connect the mechanism with the switch are changed, and a train trails the switch, will be similar to that previously described and will therefore be understood from the foregoing description and from an inspection of the drawings without further detailed description.

It should also be pointed out that, due to the fact that the biasing devices are arranged in the manner previously described, the force which is

- exerted on the points tending to restore them to their normal positions when a train trails the switch gradually decreases with the displacement of the points from their normal positions and as a result the force which must be exerted on the points by the fluid pressure device D to force them to and hold them in their reverse positions while a train is trailing the switch will be relatively small.
- 10 It should further be pointed out that, with the apparatus constructed in the manner described, since the points are forced to their full reverse positions while a train is trailing the switch, the wear on the points will be very little greater than the wear on the points of switches which are not intended to be trailed.

Although I have herein shown and described only one form of apparatus embodying my invention, it is understood that various changes and modifications may be made therein within the scope of the appended claims without departing from the spirit and scope of my invention.

Having thus described my invention, what I claim is:

- 25 1. In combination, a switch of the type adapted to be trailed, means for normally biasing said switch to one extreme position, a fluid pressure device operatively connected with said switch and provided with means for controlling the rate of movement of said switch by said biasing means, and means actuated by a train trailing said switch when said switch occupies its one extreme position for supplying fluid pressure to said fluid pressure device to cause said fluid pressure device to force said switch to its other extreme position.

- 30 2. In combination, a switch of the type adapted to be trailed, means for normally biasing said switch to one extreme position, a fluid pressure device operatively connected with said switch and provided with means for controlling the rate of movement of said switch by said biasing means, and means actuated by a train trailing said switch when said switch occupies its one extreme position for supplying fluid pressure to said fluid pressure device to cause said fluid pressure device to force said switch to and hold it in its other extreme position until after the trailing train has passed said switch.

- 35 3. In combination, a switch of the type adapted to be trailed, means for normally biasing said switch to one extreme position, a fluid pressure device operatively connected with said switch and provided with means for controlling the rate of movement of said switch by said biasing means, and means connected with said switch and actuated by the flexure of one of the movable rails of said switch while a train is trailing the switch for supplying fluid pressure to said fluid pressure device to cause said fluid pressure device to force said switch to, and hold it in, its other extreme position until after the trailing train has passed said switch.

- 40 4. In combination, a switch of the type adapted to be trailed, means for normally biasing said switch to one extreme position, a fluid pressure device operatively connected with said switch and provided with means for controlling the rate of movement of said switch by said biasing means, and a fluid pressure pump actuated by the lateral flexure of the movable rails of said switch caused by a train trailing said switch when said switch occupies said one extreme position and effective to supply fluid pressure to said fluid pressure device to cause said fluid pressure device to force

said switch to, and hold it in, its other extreme position until after the trailing train has passed said switch.

5 5. In combination, a railway switch of the type adapted to be trailed, means for normally biasing said switch to one extreme position, a fluid pressure device operatively connected with said switch and effective when said switch is moved to its other extreme position by a trailing train to retard the return movement of said switch to said one extreme position by said biasing means, and means connected with said switch and responsive to movement of the movable switch rails caused by a train trailing said switch for supplying fluid pressure to said fluid pressure device to hold said switch in said other extreme position until after the trailing train has passed said switch.

10 6. In combination, a railway switch of the type adapted to be trailed, means connected with the movable rails of said switch adjacent their points for biasing said switch to a normal extreme position, linkage connected with the movable rails of said switch at a point in rear of the point of connection of said biasing means and biased to one position in such manner that the movable rails will be sprung to less than wheel gauge width at the point of connection of said linkage with the rails when the points of the rails are forced to their reverse positions by a force applied to the movable rails adjacent their points, whereby the wheels of a train trailing said switch from its normal position will cause an oscillating motion of said linkage, a fluid pressure pump actuated by the oscillating motion of said linkage, and a fluid pressure motor connected with the movable rails of said switch and supplied with fluid pressure by said pump and effective when supplied with fluid pressure for forcing the movable rails to their reverse positions.

15 7. In combination, a railway switch of the type adapted to be trailed, means connected with the movable rails of said switch adjacent their points for biasing said switch to a normal extreme position, linkage connected with the movable rails of said switch at a point in rear of the point of connection of said biasing means and biased to one position in such manner that the movable rails will be sprung to less than wheel gauge width at the point of connection of said linkage with the rails when the points of the rails are forced to their reverse positions by a force applied to the movable rails adjacent their points, whereby the wheels of a train trailing said switch from its normal position will cause an oscillating motion of said linkage, a fluid pressure pump actuated by the oscillating motion of said linkage, and a fluid pressure motor connected with the movable rails of said switch and supplied with fluid pressure by said pump and effective when supplied with fluid pressure for forcing the movable rails to their reverse positions, means for locking said switch in its normal extreme position, and means actuated by said linkage for actuating said locking means to unlock said switch when a train trails said switch.

20 8. In combination, a spring switch, a tie rod connecting the movable rails of the switch at a point between the heel and the point of the switch, means for rigidly locking the movable rails of the switch in one extreme position, means connected with and actuated by said tie rod for unlocking the movable rails when a train trails the switch, a fluid pressure motor connected with the movable rails, and means connected with and actuated by said tie rod for supplying fluid pres-

- sure to said fluid pressure motor when a train trails the switch to force the movable rails to, and hold them in, their other extreme position until after the trailing train has passed the switch.
9. In combination, a railway switch, means for biasing said switch to one extreme position and for normally locking it in said one extreme position, linkage connected with the movable rails of said switch at a point between the heel and the point of the switch for unlocking said switch when a train trails the switch, and means actuated by said linkage for forcing said switch to its other extreme position in opposition to the bias of said biasing means when a train trails the switch.
10. In combination, a railway switch, means for biasing said switch to one extreme position, means for rigidly locking said switch in one extreme position, and means connected with one of the movable rails of said switch at a point between the heel and the point of said switch and responsive to the lateral bending of the rail which takes place when a train trails said switch for unlocking said switch and for subsequently applying to the points of the movable rails a force which opposes and exceeds that due to said biasing means until after the trailing train has passed said switch.
11. In combination, a railway switch of the type adapted to be trailed, operating mechanism for moving said switch between its two extreme positions including biasing means for yieldably urging said switch to the extreme position to which it is moved, a fluid pressure device operatively connected with said switch and effective to retard movement of said switch by said biasing means, and means actuated by a train trailing said switch for supplying fluid pressure to said fluid pressure device to cause said fluid pressure device to force said switch to, and hold it in, the extreme position toward which it is moved by the trailing train until after the train has passed the switch.
12. In combination, a switch of the type adapted to be trailed, means for normally biasing said switch to one extreme position, locking means biased to a locking position and effective when in its locking position for locking said switch in said one extreme position, linkage connecting said locking means with the movable rails of said switch and effective when a train starts to trail said switch for actuating said lock mechanism to unlock said switch, a fluid pressure device operatively connected with said switch for retarding movement of said switch by said biasing means, and means actuated by said linkage when a train trails said switch for supplying fluid pressure to said fluid pressure device to cause said device to force said switch to, and hold it in, its other extreme position until after the train has passed said switch.
13. In combination, a railway switch of the type adapted to be trailed, means for biasing the movable rails of said switch to one extreme position in such manner that when the movable rails are forced away from said one extreme position by a trailing train the biasing force will decrease with the displacement of the points, a fluid pressure device connected with the movable rails of said switch adjacent their points, linkage connected with the movable rails at a point intermediate the heel and the point of the rails and biased to one position in such manner that said linkage exerts on said rails a force which aids
- that due to said biasing means in biasing said switch to one extreme position, whereby when a train trails said switch said linkage will oscillate, and a fluid pressure pump actuated by the oscillation of said linkage and effective for supplying fluid pressure to said fluid pressure device to force the points of the movable rails to their other extreme positions while a train is trailing the switch.
14. In combination, a switch of the type adapted to be trailed, means for normally biasing said switch to one extreme position, linkage connected with the movable rails of said switch between the heel and the point of the switch and biased to one position in such manner that when a train trails said switch said linkage will oscillate, a cam oscillated by said linkage, a lever oscillated by said cam, a pump actuated by the oscillation of said lever, and a fluid pressure motor connected with the movable rails and supplied with fluid pressure by said pump for exerting on the movable rails a force which opposes and exceeds that due to said biasing means when a train trails the switch.
15. In combination, a railway switch, a switch operating mechanism comprising a casing, a switch actuating shaft journaled in said casing and operatively connected with said switch, a star block in said casing biased to one position, manually operable means for moving said shaft between two extreme positions corresponding to the extreme position of said switch and for connecting said star block with said shaft in either extreme position of the shaft to bias said switch to the extreme position which it then occupies, a fluid pressure device in said casing connected with said star block and permitting free movement of said star block away from said one position but acting to retard movement of said star block toward said one extreme position, locking means in said casing biased to a locking position and effective when in its locking position for locking said switch in one extreme position, linkage connected with said locking means and with the movable rails of said switch intermediate the heel and the point of the switch and effective when a train trails the switch for unlocking the switch, and a fluid pressure pump in said casing actuated by said linkage when a train trails said switch and effective to supply fluid pressure to said motor to cause said motor to exert a force on said star block which opposes and exceeds that due to said biasing means.
16. In combination, a switch of the type adapted to be trailed, operating mechanism for moving said switch between its two extreme positions including spring means for biasing said switch to whichever extreme position it is moved by said mechanism, a cylinder filled with fluid and containing a reciprocable piston, a fluid pressure pump connected with said cylinder and effective when operated for pumping fluid from one end of said cylinder to the other, means for operatively connecting said piston with said switch in such manner that when a train trails said switch said piston will be moved toward said one end of said cylinder, and means actuated by a train trailing said switch for actuating said pump.
17. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid from one end of said

cylinder to the other, means for operatively connecting said fluid pressure device with said switch in such manner that movement of said switch toward said other extreme position by a trailing train will move said piston toward said one end of said cylinder, and means actuated by a train trailing said switch for actuating said pump.

18. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid from one end of said cylinder to the other, means for operatively connecting said fluid pressure device with said switch in such manner that movement of said switch toward said other extreme position by a trailing train will move said piston toward said one end of said cylinder, and means responsive to the lateral flexure of the movable rails of said switch caused by a train trailing said switch for actuating said pump.

19. In combination, a switch of the type adapted to be trailed, operating mechanism for moving said switch between its two extreme positions including spring means for biasing said switch to whichever extreme position it is moved by said mechanism, a cylinder filled with fluid and containing a reciprocable piston, a fluid pressure pump connected with said cylinder and effective when operated for pumping fluid from one end of said cylinder to the other, means for permitting free relative movement of said piston toward said one end of said cylinder and for retarding movement of said piston toward said other end of said cylinder, means for operatively connecting said piston with said switch in such manner that when a train trails said switch said piston will be moved toward said one end of said cylinder, and means actuated by a train trailing said switch for actuating said pump.

20. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid from one end of said cylinder to the other, means for permitting free relative movement of said piston toward said one end of said cylinder and for retarding movement of said piston toward said other end of said cylinder, means for operatively connecting said fluid pressure device with said switch in such manner that movement of said switch toward said other extreme position by a trailing train will move said piston toward said one end of said cylinder, and means responsive to the lateral flexure of the

movable rails of said switch caused by a train trailing said switch for actuating said pump.

21. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid out of one end of said cylinder into the other end, means connected with said other end of said cylinder for storing up pressure in said other end of said cylinder, means for operatively connecting said fluid pressure device with said switch in such manner that movement of said switch toward said other extreme position by a trailing train will move said piston toward said one end of said cylinder, and means actuated by a train trailing said switch for actuating said pump.

22. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid out of one end of said cylinder into the other end, means for permitting fluid to flow freely from one end of said cylinder to the other but for restricting the flow of fluid from said other end to said one end, means connected with said other end of said cylinder for storing up pressure in said other end of said cylinder, means for operatively connecting said fluid pressure device with said switch in such manner that movement of said switch toward said other extreme position by a trailing train will move said piston toward said one end of said cylinder, and means actuated by a train trailing said switch for actuating said pump.

23. In combination, a switch of the type adapted to be trailed, means for normally biasing said switch to one extreme position, a fluid pressure device including a cylinder filled with fluid and containing a reciprocable piston, a pump connected with said cylinder and effective when operated for pumping fluid out of one end of said cylinder into the other end, a recess formed in said piston on the side adjacent said other end of said cylinder and closed by a flexible diaphragm biased to an outer position, means for operatively connecting said fluid pressure device with said switch in such manner that movement of said switch toward said other extreme position by a trailing train will move said piston toward said one end of said cylinder, and means actuated by a train trailing said switch for actuating said pump.

HERBERT L. BONE.
